UNITED STATES PATENT OFFICE.

WILLIAM A. UTTZ, SR., OF ST. LOUIS, MISSOURI, ASSIGNOR TO PERFECTION PACKAGE SEALER COMPANY, INC., OF DALLAS, TEXAS, A CORPORATION OF TEXAS.

GUMMED-TAPE-SERVING MACHINE.

Application filed November 25, 1927. Serial No. 235,671.

This invention relates to gummed tape dispensing machines and has special reference to tape guiding means for such machines.

One important object of the invention is to provide a novel and improved tape guiding means for gummed tape dispensing machines of the type shown in my prior Patent Number 1,592,431, dated July 13, 1926, Reissue Number 16,774, dated October 18, 1927.

10 A second important object of the invention is to provide an improved guide means for such machines wherein the guides are readily adjustable to accommodate different sizes of tapes and in which such guides will be located in such relation to the remainder of the machine that they will ensure that the tab formed by the machine illustrated in the before mentioned patent will be properly centered in the tape.

20 With the above and other objects in view as will be hereinafter apparent, the invention consists in general of certain novel details of construction and combinations of parts hereinafter fully described, illustrated in the 25 accompanying drawings and specifically claimed.

In the accompanying drawings like characters of reference indicate like parts in the several views, and:

30 Figure 1 is a plan view of a gummed tape dispensing machine having the improved guide means embodied therein.

Figure 2 is a view, partly in section, showing the upper guide plate and guides removed 35 from the machine.

Figure 3 is a partial plan view of a portion of the top plate of the machine which forms the lower guide plate.

Figure 4 is a detail section on the line 4—4 40 of Figure 1.

Figure 5 is a plan view similar to Figure 2 but showing a modified form of upper plate.

Figure 6 is a front view of the plate shown in Figure 2.

45 Figure 7 is a section on the line 7—7 of Figure 5.

Figure 8 is a detail perspective of one of the guide arms and its finger.

In carrying out the present embodiment of 50 the invention there is provided a casing having a top plate 10 and at the rear end of this casing are mounted suitable supports or posts 11 between which is carried the roll R of gummed tape, this being supported on a transverse axis in the form of a screw 12.

Toward the forward end of the device there is a supporting transverse shaft 13 whereon is pivoted a frame 14 carrying the severing blade 15 and the tab forming blade 16, these parts being operated by a lever 17 in any suitable manner such as that described in the prior patent above referred to. This tab forming blade operates through a die opening 18 formed in the plate 10 upon depression of the frame 14 in the usual manner. From 60 the roll the tape T is fed forward over the plate 10 and at the forward end there is provided a guide plate having side portions 19 which rest on and are secured to the side portions of the top 10 by means of screws 20. At 65 the rear this plate is offset upwardly as at 21 between the side portions 19 and thus is spaced above the plate 10 so that the tape T can pass between the lower plate 10 and the central portion 21 of the upper plate. Furthermore, this central portion 21 is provided with a slot 22 extending longitudinally from adjacent the rear and from each side of this slot there extends a lateral slot 23 positioned 70 in vertical alinement with the transverse slot 24 formed in the upper plate 10, the slots 23 and 24 accommodating the knife 15 in tape cutting position. The slot 22 is vertically alined above the die slot 18 so that when the tab is punched it may be grasped and the 75 tape drawn out. Beneath the forward end of the guide plate is located a moistening device which is here shown in the form of a brush 25 having its lower end extending downward into a tank 26 adapted to contain 80 water. Over this brush the guide plate is arched upwardly as at 27, the forward portion of this arch being cut away in the form shown in Figure 2 while in the form shown in Figure 5 the arch extends from side portion 85 19 to side portion 19, being interrupted in the middle by the slot 22.

In the plate 10 symmetrically disposed on opposite sides of the die slot 18 is a pair of arcuate slots 28 and in the upper guide plate 100 is a similar pair of arcuate slots 29 which are spaced vertically above the slots 28. Pivoted on the upper guide plate by screws 30 is a pair of swinging guide arms 31 each having a finger 32 which extends down through the slot 29 into the slot 28 and thus bridges the space between the plates where the tape moves. Indices 33 may be used to set these arms. The screws 30 also serve to hold the 105 rear end of the upper guide plate on the plate 110

10 and to clamp the arms 31 in adjusted position, this rear end being held up by small bosses 34 on its underside. It will be observed that the slots 29, being positioned opposite the die 18 center the tape at this point so that the tab formed by the tab cutter is formed centrally of such tape. It is also to be noted that the rear end of the guide plate extends upwardly as at 35 to form a guard to 10 protect the fingers of the user from the knife and tab cutter.

Obviously, the arms 31 may be swung to bring the finger 32 closer together or further apart in accordance with the size of tape 15 passing through the machine and, when so swung, may be secured in position by tightening the screws 30 if desired.

In front of the brush a cover 11' is provided to cover the front end of the water tank.

20 It will also be noted that the cover plate 21 acts as a stripper plate so that when the knife and tab cutter move upward they will not carry the tape with them.

There has thus been provided a simple and 25 efficient device of the kind described and for the purpose specified.

It is obvious that minor changes may be made in the form and construction of the invention without departing from the material 30 spirit thereof. It is not, therefore, desired to confine the invention to the exact form herein shown and described, but it is desired to include all such as properly come within the scope claimed.

35 Having thus described the invention, what is claimed as new, is:

1. In a machine for dispensing gummed tape, a tape guide including a lower plate over which a tape travels, an upper plate 40 spaced slightly above the lower plate and under which said tape travels, said upper plate having a pair of symmetrically disposed arcuate slots spaced evenly on opposite sides of the center line of movement of the tape, guide arms pivoted concentrically of the slots, and fingers projecting from the free ends of said arms through said slots and depending below the upper plate.

2. In a machine for dispensing gummed 50 tape, a tape guide including a lower plate, an upper plate spaced slightly above the lower plate to permit the passage of gummed tape between the plates, said plates having registering pairs of arcuate slots symmetrically 55 disposed on opposite sides of the passage for the tape, guide arms pivoted concentrically of said slots, and fingers on said guide arms extending through the slots of the upper and lower plates.

3. In a machine for dispensing gummed 60 tape, a tape guide including a lower plate, an upper plate spaced slightly above the lower plate to permit the passage of gummed tape between the plates, said plates having registering pairs of arcuate slots symmetrically 65

disposed on opposite sides of the passage for the tape, guide arms pivoted concentrically of said slots on top of the upper plate, and fingers on the free ends of said guide arms extending downwardly through the slots in the upper plate and entering the slots in the lower plate. 70

4. In a machine for dispensing gummed tape, a tape guide including a lower plate, an upper plate secured on said lower plate 75 at its lateral edges and having its central portion offset upwardly to form a tubular tape passage, said upper plate having a pair of symmetrically disposed arcuate slots spaced evenly on opposite sides of the center 80 line of movement of the tape, guide arms pivoted concentrically of the slots, and fingers projecting from the free ends of said arms through said slots and depending below the upper plate. 85

5. In a machine for dispensing gummed tape, a tape guide including a lower plate, an upper plate secured on said lower plate at its lateral edges and having its central portion offset upwardly to form a tubular 90 tape passage, said plates having registering pairs of arcuate slots symmetrically disposed on opposite sides of the passage for the tape, guide arms pivoted concentrically of said 95 slots, and fingers on said guide arms extending through the slots of the upper and lower plates.

6. In a machine for dispensing gummed tape, a tape guide including a lower plate, an upper plate secured on said lower plate at 100 its lateral edges and having its central portion offset upwardly to form a tubular tape passage, said plates having registering pairs of arcuate slots symmetrically disposed on opposite sides of the passage for the tape, guide arms pivoted concentrically of said 105 slots on top of the upper plate, and fingers on the free ends of said guide arms extending downwardly through the slots in the upper plate and entering the slots in the lower plate. 110

7. In a machine for dispensing gummed tape, a tape guide including a lower plate over which a tape travels, an upper plate spaced slightly above the lower plate and 115 under which said tape travels, said upper plate having a pair of symmetrically disposed arcuate slots spaced evenly on opposite sides of the center line of movement of the tape, guide arms pivoted concentrically of the slots, fingers projecting from the free ends of said arms through said slots and depending below the upper plate, and means 120 to hold the arms in adjusted positions.

8. In a machine for dispensing gummed 125 tape, a tape guide including a lower plate, an upper plate spaced slightly above the lower plate to permit the passage of gummed tape between the plates, said plates having registering pairs of arcuate slots symmetri- 130

- 5 cally disposed on opposite sides of the passage for the tape, guide arms pivoted concentrically of said slots, fingers on said guide arms extending through the slots of the upper and lower plates, and means to hold the arms in adjusted positions.
- 10 9. In a machine for dispensing gummed tape, a tape guide including a lower plate, an upper plate spaced slightly above the lower plate to permit the passage of gummed tape between the plates, said plates having registering pairs of arcuate slots symmetrically disposed on opposite sides of the passage for the tape, guide arms pivoted concentrically of said slots on top of the upper plate, fingers on the free ends of said guide arms extending downwardly through the slots in the upper plate and entering the slots in the lower plate, and means to hold the arms in adjusted positions.
- 15 10. In a machine for dispensing gummed tape, a tape guide including a lower plate, an upper plate secured on said lower plate at its lateral edges and having its central portion offset upwardly to form a tubular tape passage, said upper plate having a pair of symmetrically disposed arcuate slots spaced evenly on opposite sides of the center line of movement of the tape, guide arms pivoted concentrically of the slots, fingers projecting from the free ends of said arms through said slots and depending below the upper plate, and means to hold the arms in adjusted positions.
- 20 11. In a machine for dispensing gummed tape, a tape guide including a lower plate, an upper plate secured on said lower plate at its lateral edges and having its central portion offset upwardly to form a tubular tape passage, said plates having registering pairs of arcuate slots symmetrically disposed on opposite sides of the passage for the tape, guide arms pivoted concentrically of said slots, fingers on said guide arms extending through the slots of the upper and lower plates, and means to hold the arms in adjusted positions.
- 25 12. In a machine for dispensing gummed tape, a tape guide including a lower plate, an upper plate secured on said lower plate at its lateral edges and having its central portion offset upwardly to form a tubular tape passage, said plates having registering pairs of arcuate slots symmetrically disposed on opposite sides of the passage for the tape, guide arms pivoted concentrically of said slots on top of the upper plate, fingers on the free ends of said guide arms extending downwardly through the slots in the upper plate and
- 30 35 40 45 50 55 60 65 70 75 80 85 90 95 100 105 110
- entering the slots in the lower plate, and means to hold the arms in adjusted positions.
13. In a machine for dispensing gummed tape, a tape guide including a lower plate over which a tape travels, an upper plate spaced slightly above the lower plate and under which said tape travels, said upper plate having a pair of symmetrically disposed arcuate slots spaced evenly on opposite sides of the center line of movement of the tape, guide arms pivoted concentrically of the slots, and fingers projecting from the free ends of said arms through said slots and depending below the upper plate, said upper plate having an upwardly arched portion spaced forwardly from the slots and fingers whereby to permit formation of an upward bend in the tape in its passage from the machine.
14. In a machine for dispensing gummed tape, a tape guide including a lower plate over which a tape travels, an upper plate spaced slightly above the lower plate and under which said tape travels, said upper plate having a pair of symmetrically disposed arcuate slots spaced evenly on opposite sides of the center line of movement of the tape, guide arms pivoted concentrically of the slots, and fingers projecting from the free ends of said arms through said slots and depending below the upper plate, said upper plate further having a longitudinal slot extending forwardly from between said arms and centrally of the plate to permit a guided portion of the tape to be grasped.
15. In a machine for dispensing gummed tape, a tape guide including a lower plate over which a tape travels, an upper plate spaced slightly above the lower plate and under which said tape travels, said upper plate having a pair of symmetrically disposed arcuate slots spaced evenly on opposite sides of the center line of movement of the tape, guide arms pivoted concentrically of the slots, and fingers projecting from the free ends of said arms through said slots and depending below the upper plate, said upper plate having an upwardly arched portion spaced forwardly from the slots and fingers whereby to permit formation of an upward bend in the tape in its passage from the machine, said upper plate further having a longitudinal slot extending forwardly from between said arms and centrally of the plate to permit a guided portion of the tape to be grasped, said longitudinal slot extending through the upwardly arched portion of the upper plate.

In testimony whereof I affix my signature.
WILLIAM A. UTTZ, Sr.
